UNITED STATES PATENT OFFICE

ALEXANDER BOYNTON, OF SAN ANTONIO, TEXAS

AUTOMATIC STAGE-LIFT FLOWING DEVICE

Application filed June 1, 1927. Serial No. 195,739.

This invention relates to improvements in well flowing apparatus, and it consists of the constructions, combinations and arrangements herein described and claimed.

5 An object of the invention is to provide a flowing device which, as more fully appears later on, employs what is herein known as a revamping weight as well as a valve-plunger for partially utilizing the pressure differential inside and outside of the tubing string for the purpose of controlling the liquid-medium (gas, air or other fluid), the actual operating impulse of the revamping weight being derived from the moving liquid column, 15 the movement of which is the result of the foregoing pressure differential.

Another object of the invention is to provide a flowing device employing a certain differential principle, hereinafter announced, 20 to the extent of performing an operation upon a valve plunger which is peculiarly identified with this principle, the valve plunger serving the purpose of obtaining what is known as the seal-off at certain times 25 of the pressure fluid which raises the liquid column.

Other objects and advantages appear in the following specification, reference being had to the accompanying drawings, in which,

30 Figure 1 is a central vertical section of one form of flowing device employing, what is herein known as, a revamping weight,

Fig. 2 is a horizontal section taken substantially on the line 2—2 of Fig. 1,

35 Fig. 3 is a vertical section of another form of the flowing device operating on the same principle as the form in Fig. 1, but being adaptable to what is known as the casing method of raising liquid.

40 The invention disclosed in this application is associated with a series of other applications known as Case #1, filed April 5, 1927, Serial Number 181,144; Case #2, filed May 17, 1927, Serial Number 192,049; Case #3, filed May 19, 1927, Serial Number 192,717; and Case #4, filed May 25, 1927, Serial Number 194,122, but the association is only partial as indicated in the following respects: The inventions of the foregoing applications all have to do with the lifting of liquid, whether

that be oil, water, etc., from a well, the arrangement being such that the lifting impulses are supplied to the column of liquid being lifted at stages.

Gas, air, or other suitable pressure fluid 55 supplies the lifting impulse and the valve means of the various foregoing applications are of such design that they will operate upon the occurrence of a difference in pressure inside and outside of the tubing and, in fact, 60 depend for their operation upon such difference in pressure, this difference being commonly referred to as the differential.

A brief explanation will enable the reader to visualize conditions in a well equipped with any of the devices in the foregoing applications, and will make clear to him the meaning of the term differential. The wall of the well bore is supposedly lined with a casing which is surmounted by a casing head 70 from which a tubing string is suspended. Provision is made for discharging the liquid of the well either from the casing or from the tubing, either function being accomplished by what is known as the casing or 75 tubing method which merely imply an introduction of the fluid either into the tubing or casing.

For the time being, it is presumed that the well is to be evacuated by the tubing 80 method, and it will be understood from the foregoing statement that pressure fluid is introduced into the well casing in order to bring this about. An imposition of pressure upon the liquid in the casing will cause a 85 column of the liquid to rise in the tubing, it being quite apparent that a condition will be assumed when the elevated liquid column and the external pressure fluid will balance 90 each other. It is now that the improved valve devices function.

An opening of the valve device nearest to the liquid level in the casing will permit the influx of fluid pressure into the tubing and into the liquid column contained thereby so 95 that the liquid column is given an upward impulse. As the liquid column is thus made to rise, it will be evident that the back pressure of the liquid will tend to counteract the pressure on the outside. As the next lower 100

valve device is uncovered by the receding liquid level in the casing, a similar happening occurs, and the reader can readily visualize the situation of a plurality of the valve devices acting according to the fluid pressure on the outside and the varying back liquid-pressure on the inside in determining the position thereof.

The present invention utilizes the differential principle only partially, the plunger structure herein disclosed being the indicator of the fact that the differential principle is used. The outstanding feature of the present invention is what will be known as a revamping weight, the term "revamping" being defined, for the purposes of the present description, as re-forming or re-conditioning the fluid which is acted upon and which actuates the so-called revamping weight.

20 Reference is had to the drawings:

Tubing sections 1 must be regarded as part of a long tubing string suspended in a well, the casing of which is not shown. The valve device is indicated at 2, this being a body of suitable shape serving the purpose of a cylinder in which the revamping weight 3 reciprocates. The revamping weight acts somewhat like a piston.

A bushing 4 serves as a coupling between the tubing string and the valve body 2, the bushing being bored at 5 to provide the necessary liquid conduit, counter-bored at 6 to provide a chamber for the collar 7 of the revamping weight and circularly rabbeted at 8 to provide a recess at the base of which one end of a spring 9 is seated.

The opposite end of the foregoing spring occupies a circular groove 10 on top of the circular flange 11 of the revamping weight.

40 This flange may be known as a bearing flange in that it has a plurality of peripheral recesses 12 in which ball bearings 13 are pocketed. These greatly reduce the friction of movement of the revamping weight.

45 A base flange or piston 14 of the revamping weight has a recess 15 by which the extension 16 of the plunger 17 is received. Inasmuch as some turning movement of the revamping weight is expected and possibly desired, the recess 15 is made in the form of a circular groove, the idea being to always afford a recess for the reception of the extension 16 regardless of how much the revamping weight may turn.

55 It is observed that the periphery of the base flange 14 has a thin circular extension or skirt 18 which is adapted to rest upon the shoulder 19 of the body 2 and face the extremity 20 of the weight passageway 21 slightly above the shoulder as at 22 thus to admit liquid to the circular recess 15 and assist in raising the weight, although this lifting effort of the liquid or fluid is by no means relied upon to perform the intended function of revamping the liquid or fluid.

Turned edges at the extremity 20 as well as at the uppermost part of the throat 23 help in defining the chamber 22 previously alluded to. It is important to observe at this point that the passage 21 diminishes from the bottom to the top, the bottom diameter being larger than that of the top. It will be instantly understood that an expansion of the liquid or fluid in the space 22 and at the bottom of the passage 21 will at once be followed by a contraction of the liquid or fluid as it moves upwardly in the passage 21 and reaches the smaller portion thereof. The restriction of the passage thus remodels or reforms, so to speak, the rapidly moving fluid or liquid, this re-vamping of the fluid and the engagement thereof with the tapering wall of the passage 21 supplying the energy to raise the weight 3 for the release of the plunger 17.

Reverting to the plunger, it is observed that a chamber 24 provides a housing in which the plunger is situated. One end of an inlet port 25 in the plug 26 provides the seat for the plunger 17. An annular restriction 27 leaves an outstanding circular flange 28 which is spirally grooved at 29 to cause turning of the plunger by action of the by-passing fluid. The continuation of the restriction 27 beyond the flange 28 provides a valve end 30 which is capable of engaging the upper seat 31. The following dimensions are given for the exemplification of the practical manufacture of the device. The difference in diameter between the plunger and the plunger chamber bore should be from .005" to .025". The difference in diameter between plunger shank 16 and discharge port through which it works should be greater than the difference in diameters first mentioned for the reason that the diameters first mentioned must govern without interference by restricted passage around the plunger extension 16.

The devices should be so spaced in the tubing string that the weight of fluid in the tubing between adjacent devices is from one-fourth to one-half as much as the pressure per square inch required to compress the spring and thereby force the plunger to sealing-off engagement upon its upper seat. For illustration, assume the weight of the fluid between any two adjacent devices to be 30 lbs. per square inch, then the pressure per square inch required to compress the spring and seal-off the plunger upon its upper seat should be 60 lbs. to 120 lbs.

The above spacing gives the best results and states the spacing rule correctly, but flow will be initiated and maintained if the weight of the fluid per square inch between the valves is only slightly less than the pressure per square inch required to compress the spring sufficiently to cause the plunger to seal-off upon its upper seat. For illustration assume the weight of the fluid between any two adjacent devices to be 30 lbs. per square inch, then the pressure per square inch required to compress the spring and seal-off the plunger upon its upper seat should be 60 lbs. to 120 lbs.

cent devices to be 30 lbs. per square inch, then the pressure per square inch required to compress the spring until the plunger seals-off upon its upper seat must be slightly over 30 lbs. and should, as first stated, be from 60 lbs. to 120 lbs.

In this case, however, it will be noted that there is considerable weight represented by the member contacting with lower end of 10 spring. This weight will correspondingly reduce the spring tension required to produce the seal-off at desired pressure.

The operation is readily understood. It is to be observed, first of all, that there is a slight space between the extremity of the extension 16 and the adjacent recess 15 thus affording sufficient room for a slight upward movement of the plunger 17 to admit fluid pressure from the surrounding casing (not shown) to the interior of the tubing string 1.

It is assumed that there is fluid (gas or air) in the casing surrounding the tubing at a pressure of 200 pounds. This fluid is admitted from any suitable source. The reader 25 can readily imagine a valve in the tubing string, sometimes referred to as the flow line. This valve is for the time being, supposed to be closed, but by virtue of the permissible movement of the plunger 17, there 30 will be an equalization of fluid pressures inside and outside of the tubing string as well as an arrival at a common level of the liquid in both the casing and tubing.

It will, of course, be apparent that different flowing conditions, depth of well, 35 volume of fluid, specific gravity of fluid, degree of aeration, etc., will require a number of variations and adjustments in the general assembly and construction of this device 40 without materially affecting the principles involved and the general types of construction embodied to properly utilize the same.

Certain working conditions, especially 45 where larger volumes of compressed air, gas or other means are applied, will cause the device to function more efficiently if revamping weight 3 is in its lowermost position. This, of course, would require that extensions 18 be shortened to allow such contact. 50 Such construction, while apparently holding base 17 of plunger 27 upon its lower seat, and consequently apparently in the closed position, is in fact for all practical purposes, the open position for the reason 55 that any appreciable differential will cause plunger 27 to rise by direct pressure and consequently lift revamping weight 3 to the extent of allowing lifting energy to enter chamber 21 at all proper times to speed up 60 the moving column whenever the same slows down by reason of a falling differential.

To illustrate, let us assume that the area of port 25 is $\frac{1}{4}$ " and that the cross sectional area of plunger base 17 is 1" and that revamping weight 3 and plunger 27 have a

combined weight of five pounds. Assume plunger base 17 to be firmly seated upon port 25 and revamping weight 3, of course, to be seated upon plunger end 16. 20 pounds per square inch of differential will therefore be required to unseat plunger base 17 because the cross sectional area of port 25 is $\frac{1}{4}$ ", and the weight of plunger and revamping weight is 5 pounds, these factors being given as an example. Instantly, however, 70 after the seal-off is broken between plunger end 17 and port 25 the pressure is transferred to the larger area (1 sq. inch) of plunger 17. As long thereafter as 5 pounds of differential can act upon plunger base 17 the same will 75 remain unseated, and in the intaking position. Some loss of pressure will, of course, result from the fact that there is by-passing space between plunger 27 and plunger chamber 24.

By enlarging port 25 to an area only slightly less than plunger base 17, a direct pressure of slightly more than 5 pounds will cause an unseating of the plunger and intaking through the valve. This intaking at 80 approximately 5 pounds of pressure results in a jetting effect which is mechanically beneficial, especially in air or gas lifts of heavy or viscous fluids.

To cause the well to flow, open the valve 85 in the tubing string. The fluid (gas or air) within the tubing and under 200 lbs. pressure, is thus released, and the liquid level within the tubing begins to rise rapidly by virtue of the 200 lbs. pressure of the fluid 100 outside of the tubing upon the well liquid exterior of the tubing.

An actual installation of the invention requires numerous valves connected in the tubing string at intervals. The uppermost valve 105 now instantly closes in the following manner: The rapid rush of pressure fluid through the revamping weight 3 raises this weight by virtue of the action upon the tapering passage 21, releasing the extension 16 110 to the extent that the valve end 30 may engage the seat 31, thus causing a seal-off at this point.

The next lower valve acts likewise, each 115 successively lower valve closing in rhythmic succession until a point is reached where the upward movement of pressure fluid (or liquid) is too slow to lift the revamping weight. The revamping weight will, therefore, at 120 that point, remain seated upon the plunger extension 16, but the spacing between the plunger extension and the recess 16 will permit the by-passing of sufficient pressure fluid to keep the liquid column moving. The liquid level in the surrounding casing will 125 continue to lower until the next lower valve is exposed for functioning to the end of admitting pressure fluid at such location.

When this next lower valve thus functions, the rapidly rising liquid column picks up or 130

raises the revamping weight 3 of the valve above, thereby permitting the associated plunger 17 to seat and seal-off the intaking means of said valve. The plunger 17 is so constructed that it will rise and seal-off at a differential of 1 lb. (that is to say, a difference of 1 lb. more on the outside than on the inside of the tubing string), after the revamping weight 3 has been lifted by the velocity of the liquid column. The revamping weight is subject to operation by the moving liquid column, this movement being the result of a pressure differential within and without the tubing string.

It is observed in Fig. 1 that the revamping weight 3 is formed much on the order of a shell, that is to say, the wall around the passage 21 is relatively thin. All that space appearing around the well intermediately of the flanges 11 and 14 may, in practice, be made smaller in case particular flowing conditions require additional weight. It is thus optional whether the spring 9 be employed for it is evident that added weight will serve in lieu of the spring. It is probably more desirable to turn the revamping weight away as indicated and to employ the spring, because then the contacting surface is reduced to a minimum as is also the likelihood of the revamping weight becoming stuck by the lodgement of mud or other foreign matter between the weight and wall of the body 2.

Fig. 3 illustrates a modification of the revamping weight type of flowing device adaptable to the casing method of lifting the liquid from the well. Such parts as correspond with similar parts in Fig. 1 are designated with similar characters without a repetition of the description.

It is observed that the valve body or cylinder 2 is now considerably elongated, and that it forms both a mounting and guide for the revamping weight 3 of general cylindrical formation. The valve body 2 has a port 32 at which pressure fluid may escape from the tubing string 1 into the well casing now indicated at 33. Incidentally, it may be observed that the bushing or coupling 4 has projections or wings 34 which centralize the position of the valve and prevent obstruction to the flowing space around the tubing string.

For the purpose of understanding the operation of the modification in Fig. 3, the reader must assume the tubing string 1 as being connected with the source of pressure fluid, and the top of the casing 33 as being equipped with a valve which may be opened to permit the flow of liquid. The reader must remember that there is an equality of fluid pressure on the interior and exterior of the tubing string and that the liquid stands at a common level both within the tubing and casing while flow line is closed.

Upon opening of the foregoing valve, the compressed fluid in the casing will at once

rush upward thus lifting the revamping weight 3 by virtue of impact with the circular flange 11. The fluid pressure on the inside of the tubing string seeks to escape at the port 32, and inasmuch as the lifted revamping weight 3 offers no obstruction, the plunger 17 is raised until the valve end 30 firmly engages the seat 31 thus sealing this point of egress against further escape of fluid pressure.

The same action occurs in respect to each valve device in rhythmic downward succession, until a point or condition is reached where the moving liquid column fails to exert sufficient lifting energy upon the circular flange 11 to hold the revamping weight in the suspended position, thus permitting the revamping weight to settle back and press down upon the extension 16 sufficiently to disengage the plunger from the seat 31 and permit the escape of pressure fluid from the tubing string through the port 32 and into the liquid in the casing for the application of the necessary lifting energy at that point.

Rapid upward movement of the liquid column in the casing indicates that no additional energy need be supplied at the point where such rapid movement occurs. On the other hand the absence of rapid upward movement indicates that lifting energy is needed, and when such condition exists the consequent settling back of the revamping weight upon the plunger extension unseats the plunger, as just stated, letting enough pressure fluid out of the tubing into the casing to accomplish the intended purpose of imparting the necessary speed to the lagging liquid column.

Although the forms of the revamping weight in Figs. 1 and 3 are somewhat dissimilar, it will be observed that each is subject to the same principle of operation; it is the action of the upwardly moving liquid column upon the weight that raises the weight from the plunger permitting a sealing-off against the escape of pressure fluid. It is apparent that the sealing-off function can operate only when the velocity of the liquid stream is sufficiently great to fully lift the weight and hold it in suspension from the recession upon the plunger projection 16.

While the construction and arrangement of the revamping weight type of flowing device is that of generally preferred forms, obviously modifications and changes may be made without departing from the spirit of the invention or the scope of the claims.

I claim:

1. A device of the character described comprising a tubing extensible into a body of liquid, valve means associated with the tubing for controlling the admission of pressure fluid from one side to the other of the tubing into a volume of the liquid at said other side of the tubing, and means subject to movement independently of said valve means ac-

cording to the velocity of liquid moving thereby on said other side of the tubing thus to determine the extent of operation of the valve device.

2. A device of the character described including a tubing extensible into a body of liquid to be flowed, a valve device situated in a passageway affording communication between the interior and exterior of the tubing and being subject in its operation to a difference in pressure inside and outside of the tubing, and means tending to hold said valve device from such position when it will prevent the flow of pressure fluid through said 10 communicating passageway but being capable of suspension in the liquid stream when the velocity thereof becomes sufficiently great by virtue of the addition thereto of pressure fluid thus permitting the valve device to close 20 said passageway.

3. A device of the character described comprising means constituting a conduit in which there is adapted to be a flow of fluid, means so disposed within the conduit that the pressure imposed thereupon by virtue of the flowing fluid tends to suspend said means within the fluid stream the degree of suspension varying in accordance with the velocity of the fluid stream and the consequent degree 25 of pressure upon said means, and an independent valve device in position to control the admission of fluid into said conduit whereby said velocity is established, the controlling positions of said valve device being 30 supervised and regulated by the degrees of suspension of said first means.

4. A device of the character described comprising means constituting a conduit in which there is adapted to be a flow of fluid, means 40 partially subject to determined differences in pressure inside and outside of the conduit to perform a sealing-off action upon the flow of fluid from one side to the other of the conduit at a designated point, and independent 45 means subject to variable operation by the variable velocity of fluid flowing in the conduit to impose a controlling effect upon said first means.

5. A device of the character described comprising means constituting a conduit in which there is adapted to be a flow of liquid, there being provision for maintaining a pressure of fluid outside of the conduit, valve means partially subject to determined 55 difference in liquid and fluid pressure inside and outside of the conduit to perform a sealing-off action upon the flow of pressure fluid through a passage affording communication between the interior and exterior of the conduit, and independent means in the conduit subject to variable operation by the variable velocity of liquid flowing therein by virtue of the impulse supplied thereto by the pressure fluid, said independent means imposing a 60 controlling effect upon said valve means and

permitting sealing-off thereof when the liquid velocity reaches a determined point.

6. A device of the character described comprising means constituting a conduit in which there is adapted to be a flow of liquid there 70 being provision for maintaining a pressure fluid outside of the conduit, means located within and defining part of the conduit being capable of axial movement and subject in such movement to the velocity of a liquid column moving in the conduit, and, valve means situated in a passage affording communication between the interior and the exterior of the conduit through which passage pressure fluid is admissible for the moving 75 of said liquid column, said valve means being subject to control by the varying positions of said first means.

7. A device of the character described comprising means constituting a conduit in which there is adapted to be a flow of liquid there 80 being provision for maintaining a pressure of fluid at one side of the conduit, means located within the conduit and being so arranged that a column of liquid flowing thereby will impose such pressure thereupon as to move it in its position within the conduit, valve means situated in a passage affording communication between the interior and exterior of the conduit through which passage pressure of fluid is admissible for the moving of said 85 liquid column, and an extension including a flange upon said first means being so associated with the valve means as to effect control 90 of the valve means according to varying positions of said first means.

8. A device of the character described comprising a valve body having a passage, means situated in the valve body and forming part of a conduit therethrough having a constriction upon which a moving liquid column may act to move said means in the axial direction to an extent determined by the velocity of movement of the liquid column and valve means situated in said passage affording communication between the interior and exterior of the valve body and being subject in its control of the admission of pressure fluid from the exterior to the interior of the valve body by virtue of various positions of said 100 first means in the valve body.

9. A device of the character described comprising means constituting a fixed conduit in which there is adapted to be a flow of liquid, a member constituting a movable part of the conduit having a constriction through which the liquid moves causing such compression of the liquid as in turn will move the member, and independent valve means in position to control the admission of fluid under pressure to the conduit to supply a moving impulse to the liquid column, said valve means being governed in its permissible action by 110 said member.

10. A device of the character described 115

comprising means constituting a fixed conduit, a valve body connected in the conduit, a cylindrical weight located within the valve body having a constricted passageway 5 through which a liquid column is adapted to flow causing axial movement of the weight due to impact against the constriction and according to the velocity of the liquid flow, and a valve device situated in a passage in the 10 valve body affording communication between the interior and exterior of the conduit, said valve device being governed in its permissible action by said weight.

11. A device of the character described 15 comprising means constituting a fixed conduit, a valve body connected in the conduit, a cylindrical weight located within the valve body having a constricted passageway through which a liquid column is adapted to flow causing axial movement of the weight due to impact against the constriction and according to the velocity of the liquid flow, a 20 valve device situated in a passage in the valve body affording communication between the 25 interior and exterior of the conduit, said valve device being governed in its permissible action by said weight, and resilient means including a spring assisting the weight intending to hold the valve device in a determined 30 position.

12. A device of the character described comprising means constituting a conduit, a valve body situated in the conduit and having a passageway affording communication 35 between the interior and the exterior, a weight situated in the valve body having a passageway tapering from one end to the other in the direction of liquid flow in the conduit, and a valve device located in the first 40 passageway to control the influx of pressure fluid into the valve body and liquid column therein, the action of said valve device being governed by the weight which is subject to varying positions in respect to the valve device by virtue of variations in the velocity of 45 the liquid column.

13. A flowing device comprising a valve body having a passageway, a movable weight situated in the valve body having a tapering 50 passageway and flanges one of which has a recess, bearing means associated with the other flange reducing the friction of movement of the weight, and a valve device situated in the first passageway to control the 55 passage of pressure fluid in respect to the valve body, said recess receiving a portion of the valve means and being in position to receive the impact of the pressure fluid.

14. A flowing device comprising a valve 60 body having a passageway, a valve device located in said passageway for controlling the flow of pressure fluid through said passageway, and a weight slidably mounted in reference to the valve body coacting with the valve 65 device having a flange receiving the impact of

a moving liquid column thus exercising a control over the valve device according to the velocity of said column.

15. A flowing device comprising a valve body having a passageway, a plunger operable in the passageway and having an extension, a coupling bushing associated with the valve body, a cylindrical weight movable in respect to the valve body having a flange confronting the bushing and a flange coacting with the plunger extension, and resilient means interposed between the first flange and bushing. 70

16. A flowing device comprising a valve body having a passageway and a shoulder, a plunger operable in the passageway and having an extension passing through the shoulder, a cylindrical weight movable in respect to the valve body, a flange on the weight having a recess confronting the extension, and a skirt on the flange engaging the shoulder to space the extension from the bottom of the recess. 80

17. A flowing device comprising a valve body having a passageway and a shoulder, a plunger operable in the passageway and having an extension passing through the shoulder, a cylindrical weight axially and rotatably movable in respect to the valve body, and a flange confronting the shoulder and having an annular recess receiving the end of the plunger extension at any revolved position of the weight. 85

18. Apparatus of the character described comprising means constituting a conduit in which a column of liquid may be lifted, an element forming part of the conduit being variously movable by varying velocities in movement of the liquid column, and an independent valve element for the control of admission of pressure fluid to the conduit for imparting lifting energy to the liquid column, said valve element being regulated in its positions by the various movement of said foregoing element. 90

19. Apparatus of the character described comprising means constituting a conduit in which a column of liquid may be lifted said means including a shell having a valve casing with a passageway affording communication between the interior and exterior of the conduit, an element forming part of the conduit being variously movable in said shell by varying velocities in movement of the liquid column, and a valve element operable in the passageway by the pressure of fluid seeking to enter the conduit but being controlled in its admissive positions by the varying positions of said first element. 110

20. Apparatus of the character described comprising means constituting a liquid conduit, a shell forming part of the conduit having a formation comprising a valve casing which has a passageway affording communication between the interior and exterior said 125

passageway including a seat, a valve element operable in the passageway toward a sealing-off engagement with the seat and having a stem extending past the seat, and a revamping element operable in the shell by varying velocities in movement of a liquid column said element including a flange engageable with the stem at predetermined times.

21. Apparatus of the character described comprising means constituting a liquid conduit, a shell connected in the conduit having a formation providing a valve casing which has a passageway for the introduction of external pressure fluid to the interior of the conduit said passageway having a seat, a valve element operable in the passageway by the pressure of fluid flowing therein, a revamping element forming part of the conduit and being movable in the shell by varying velocities in movement of the liquid column, and a piston forming part of the revamping element being guided in the shell and extending over the stem to effect a control of the valve element, there being a space between said piston and the extremity of the stem permitting unobstructed motion of the valve element for the initial introduction of a charge of pressure fluid.

22. Flowing apparatus comprising a shell having a passageway affording communication between the interior and exterior, a valve operable in the passageway to control the flow of pressure fluid therethrough, and an element movable axially in respect to the shell by a flow of liquid engendered in the shell by an admission of pressure fluid at said passageway, having means engageable with the valve tending to urge it to a seating position.

23. Flowing apparatus comprising a shell having a passageway affording communication between the interior and exterior, an element movable longitudinally in respect to the shell by a flow of liquid in the shell engendered by pressure fluid admitted at said passageway, and a valve capable of sealing off either end of the passageway, being engageable with a part of and movable with said element after a free initial movement of said valve.

24. Flowing apparatus comprising a shell having a passageway affording communication between the interior and exterior, an element forming part of a conduit in which a flow of liquid is engendered in the shell by pressure fluid admitted at said passageway and being movable rectilinearly by said liquid flow, and a valve controlling the admission of pressure fluid in said passageway, being engageable by a part of said element to produce movements of the valve in harmony with those of said element during the major actions of the valve and said element.

ALEXANDER BOYNTON.
